LINE SECURING DEVICE

Edward C. Behnke, Chicago, Ill.

Application April 28, 1937, Serial No. 139,361

18 Claims. (Cl. 24—129)

This invention relates to line securing devices.

An object of the invention is to provide a simple, practical, and inexpensive device of the character described.

Another object is to provide an improved device of the character described adapted for novel attachment of the ends of a cord, such as a clothes line or the like.

Another object is to provide a device of the character described by which a cord, such as a clothes line, may be readily adjusted to various lengths and made taut without the necessity of knotting the same.

Other objects and advantages will appear and be brought out more fully in the following specification, reference being had to the accompanying drawing, wherein:

Fig. 1 is a fragmentary view of a room illustrating the invention in use.

Fig. 2 is a side view, partially in section, of an embodiment of the invention.

Fig. 3 is a cross section of the same taken along the line 3—3 of Fig. 2.

Fig. 4 is a view similar to Fig. 3 illustrating a modification of the structure of Figs. 2 and 3.

Fig. 5 is a view, partly in section, of a modified form of the invention.

Fig. 6 is a separate perspective view of one of the parts shown in Fig. 5.

Referring more particularly to the drawing, the invention consists essentially of a pin 10 having the general characteristics of the three-legged clothes pin shown and described in the applicant Behnke's patent, No. 2,071,812, and co-pending application, Serial No. 103,822, filed October 3, 1936, the device of the present application being substantially shorter and preferably constructed of a molded or cast synthetic material such as Bakelite or other by-products of phenol-condensation. The device has a shank 11, a flanged head 12, further characterized by concave portion or top concavity 13 at one end, so-formed to facilitate attaching the device to a cord by permitting application of a finger there-

to in holding the device while applying the same to a cord or line. Three triangularly disposed and equally spaced legs 14 are formed integrally with pin 11, and have flared ends 15 and line contact surfaces 16, which contact surfaces may be flat, forming relatively sharp, angular or obtuse-angled meeting edges 17 as in Fig. 3, or curved as at 17a in Fig. 4. A lug or ear 18 is formed integrally with, or otherwise suitably secured to, the outer portion of one of the legs 14 at a position adjacent the point of merger of

the upper end of the leg with the shank 11 or the bight or crotch of the pin. An aperture or eye 19 is formed in the ear 18 and adapted to receive one end 20 of the cord or line 21, which may be attached thereto in any suitable manner, such as a knot 22. An example of the operation of the device is exemplified in Fig. 1, wherein in the line 21 is seen to be secured at each end to a towel rack 23 secured to opposite walls 24 of a room, such attachment being obvious, that after one end of the line is secured by one of the pins, the line may be drawn taut and the pin at the other end of the line secured thereto, in the usual manner, cord 21 being flexed or bent and passed through two angularly related slots or recesses 10 leading into the central bore to bind the same, substantially as shown in Figs. 3 or 4, from which it will be clear that the line is made secure against slipping.

In Figs. 5 and 6 is shown a modification of the invention, wherein a sleeve 25 is employed, which is provided with a bore 26 adapted to receive or be slipped over legs and shank of and against the flanged head of a pin 27, which pin is substantially similar to pin 10 except that the ear 25 18 is omitted. The sleeve 25 is provided with an ear 28, which in turn has an aperture 29 adapted for the end 20 of the cord 21, substantially, as described in connection with Figs. 2, 3, and 4.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to secure by Letters Patent is:

1. A device of the character described comprising a shank having a generally cylindrical contour and a central end bore and radial recesses merging therewith whereby to define spaced legs extending therefrom, and means on the shank adapted for the attachment of one end of a cord to a side portion of the shank.

2. A device of the character described comprising a shank having a generally cylindrical contour and a central end bore and radial recesses merging therewith whereby to define spaced legs extending therefrom, and means on the shank adjacent the point of merging of the upper ends of the legs with the shank adapted for

- the attachment of one end of a cord to a side portion of the shank, said means including an ear having an aperture.
3. A device of the character described comprising a shank having a generally cylindrical contour and a central end bore and radial recesses merging therewith whereby to define spaced legs extending therefrom, and means adapted for the attachment of one end of a cord to a side portion of the shank, said means including an apertured ear projecting from one side of the shank adjacent the crotch of the pin on one of said legs.
4. A device of the character described comprising a shank having a generally cylindrical contour and a central end bore and radial recesses merging therewith whereby to define three spaced legs extending therefrom, and means adapted for the attachment of one end of a cord to a side portion of the shank, said means including an apertured ear on one of said legs and adjacent said shank.
5. A device of the character described comprising a shank having a generally cylindrical contour and a central end bore and radial recesses merging therewith whereby to define spaced legs extending therefrom, and means adapted for the attachment of one end of a cord to a side portion of the shank, said means including a sleeve for said shank having an apertured ear.
6. A device of the character described comprising a shank having a generally cylindrical contour and a central end bore and radial recesses merging therewith whereby to define equally spaced legs extending therefrom, and means adapted for the attachment of one end of a cord to a side portion of the shank, said means including a sleeve detachably secured to said shank and having an apertured ear.
7. A device of the character described comprising a shank having a generally cylindrical contour and a central end bore and radial recesses merging therewith whereby to define three equally spaced legs extending therefrom, and means adapted for the attachment of one end of a cord to a side portion of the shank, said means including a sleeve detachably secured to said shank and having an aperture ear extending laterally therefrom.
8. A device of the character described comprising a shank having a concavity at one end thereof and a plurality of spaced legs extending from the other end of the shank, and means extending out from the shank adjacent the juncture of the legs with the shank adapted for the attachment of one end of a cord thereto, the cord being extended angularly through spaces between the legs to anchor the pin on the cord.
9. A line securing device as described adapted to hold a line under tension when an end portion thereof is passed around an anchoring element, said device comprising a shank having a generally cylindrical contour and a central end bore and radial recesses merging therewith to form line receiving portions, a head and three equally spaced legs extending therefrom, and an apertured ear on one of said legs adjacent said shank, whereby to secure the end of said line, said device adapted to be secured to the main portion of said line by said legs.
10. A line securing device comprising a body having a general cylindrical contour and a central end bore and three radial recesses merging therewith whereby to define three equally spaced legs of equal width and thickness, and an out-
- standing apertured ear on the body in line with one leg adjacent the crotches of the recesses for receiving and anchoring one end of a line, said line when doubled on itself being extended angularly through two of the recesses nearest the ear for holding the line taut and to adjustably anchor the device thereon.
11. A line securing device comprising a body having a shank with a flanged head having a top concavity and a central end bore and radial recesses merging therewith whereby to define spaced legs and a lug projecting from the pin adjacent the bight portions of the recesses in a direction substantially normal to the length of the body and having an aperture in the direction of the body as and for the uses and purposes specified as and for the purposes set forth.
12. For use in a line securing device, a clothes pin including a body having a general cylindrical contour and a central end bore and radial recesses merging therewith whereby to define three spaced legs, the inner faces of the legs and the recesses being disposed in obtuse-angled relation to each other, opposed faces of the recesses being substantially parallel and the inner faces of each leg defining an angular meeting edge with the faces extending in obtuse angled relation to each other for frictionally engaging and holding a line bent through adjacent recesses and extended in the same general direction at each side thereof.
13. A line securing device including a body having a general cylindrical contour and a central end bore and radial recesses merging therewith whereby to define three spaced legs, the inner faces of the legs and the recesses being disposed in obtuse-angled relation to each other, opposed faces of the recesses being substantially parallel and the inner faces of each leg defining a relatively sharp meeting edge for frictionally engaging and holding a line bent through adjacent recesses and extended in the same general direction at each side thereof, and a lug projecting from the pin adjacent the bight portions of the recesses in a direction substantially normal to the length of the body, and having an aperture in the direction of the body for anchoring one end of a line substantially at a point in a plane perpendicular to the body and closely adjacent the plane of the line passed through the recesses.
14. A line securing device including a body having a central end bore and radial recesses merging therewith whereby to define spaced legs, the inner faces of the legs and the recesses being disposed in obtuse angled relation to each other, opposed faces of the recesses being substantially parallel and the inner faces of each leg defining a meeting edge for frictionally engaging and holding a line bent through adjacent recesses and extended in the same general direction at each side thereof, and a lug projecting from the pin adjacent the bight portions of the recesses in a direction substantially normal to the length of the body, and having an aperture in the direction of the body for anchoring one end of a line substantially at a point in a plane perpendicular to the body and closely adjacent the plane of the line passed through the recesses.
15. A line securing device comprising a body having a shank provided with a slot with an obtuse-angled bend extending from one end and forming spaced legs, and an apertured ear on one leg in line with the central portion of the slot to secure the end of a line and another portion

5 of the line extending through the slot to anchor the device on the line, the aperture of the ear being in line with and parallel to the axis of the body and shank, and all portions of said line being substantially in the same horizontal plane.

10 16. A device of the character described comprising a relatively cylindrical shank and an apertured ear outstanding thereon centrally and diametrically of the shank with the aperture extending longitudinally of the shank adapted to secure the end of a cord, said shank having a longitudinal slot therein forming legs adapted to secure said cord therein.

15 17. A device of the character described comprising a relatively cylindrical shank and an apertured ear thereon projecting outwardly therefrom at right angles to the axis of the

shank to secure the end of a cord, the aperture of the ear extending in the direction of the length of the shank and said shank having an angular slot therein forming legs adapted to secure said cord therein.

10 18. A line securing device comprising a body having a general cylindrical contour and a central end bore and radial slots merging therewith whereby to define spaced legs, and an outstanding apertured ear on the body adjacent the 15 crotches of the slots for receiving and anchoring one end of a line, said line when doubled on itself being extended angularly through the slots nearest the ear for holding the line taut and to adjustably anchor the device thereon.
